By W. W. Williamson, Atty.

UNITED STATES PATENT OFFICE.

HENRY F. WORNER, OF PHILADELPHIA, PENNSYLVANIA.

DESIGN FOR A COMBINED RADIO CONTROL LEVER AND DIAL.

Application filed August 21, 1924. Serial No. 10,511. Term of patent 14 years.

To all whom it may concern:

Be it known that I, HENRY F. WORNER, a citizen of the United States, residing at Philadelphia, in the county of Philadelphia and State of Pennsylvania, have invented a new, original, and ornamental Design for a Combined Radio Control Lever and Dial, of which the following is a specification, reference being had to the accompanying drawing.

Figure 1, is a front elevation of the combined radio control lever and dial embodying my new design.

Figure 2, is an edge view thereof.

What I claim is—

The ornamental design for a combined radio control lever and dial, as shown.

HENRY F. WORNER.
